Joseph C. Robert, Jr.
BY
Cyrus N. Anderson
ATTORNEY.

UNITED STATES PATENT OFFICE.

JOSEPH C. ROBERT, JR., OF AGRICULTURAL COLLEGE, MISSISSIPPI.

LAMP-WICK REGULATOR.

1,394,354.

Specification of Letters Patent.

Patented Oct. 18, 1921.

Application filed February 19, 1921. Serial No. 446,236.

To all whom it may concern:

Be it known that I, JOSEPH C. ROBERT, Jr., a citizen of the United States, and a resident of Agricultural College, in the county of Ok- 5 tibbeha and State of Mississippi, have invented an Improvement in Lamp-Wick Reg- 10 uulators, of which the following is a specifica- 15 tion.

My invention relates to devices for regu- 10 lating the wicks of oil lamps, stoves and the like, and it has for its principal object to pro- 15 vide a device by means of which such wicks may be quickly raised or lowered and adjust- 20 ed with accuracy and precision to the exact 25 point desired.

A further object of my invention is to sim- 10 plify and cheapen the construction of devices 15 for the purpose stated.

A still further object of my invention is 20 to provide a device for regulating the wicks 25 of oil lamps, oil stoves and the like which may, without previous adjustment or manip- 30 ulation, be moved in either direction; that is, 35 up or down, for the purpose of causing like 40 up or down movement of the wick.

Other objects and advantages of my inven- 30 tion will be pointed out in the detailed de- 35 scription thereof which follows or will be ap- 40 parent from such description.

In order that my invention may be readily 35 understood and its practical advantages 40 more fully appreciated, reference may be 45 had to the accompanying drawing in which I 50 have illustrated one form of a convenient 55 embodiment thereof. However, it will be 60 understood that the said invention is sus- 65 ceptible of embodiment in other forms of 70 construction than that shown and that 75 changes in the details thereof may be made 80 within the scope of the claims without de- 85 parting from said invention.

In the drawing:

Figure 1 is a central vertical section of a 45 lamp provided with a device embodying my 50 invention for regulating the lamp wick;

Fig. 2 is a transverse sectional view taken 55 along the line 2—2 of Fig. 1; and

Fig. 3 is a side elevation of the portion of 60 the structure to which the device embodying 65 my invention is applied.

Referring to the drawing: 1 designates 65 the lamp bowl or oil reservoir having a cen- 70 tral opening in its top, as indicated at 2, 75 through which a cylinder or tube 3 extends, 80 the said tube being secured to the edges of the 85

opening 2 and the upper end thereof extending 90 a distance above the top of the bowl 1 and 95 the lower end thereof to a point a distance 100 above the bottom of the said bowl, as shown 105 in Fig. 1 of the drawing. 4 designates a cen- 110 tral tube which constitutes a guide for the 115 circular wick 5 of suitable fabric, such as 120 cotton. The said wick is supported in the 125 annular cylindrical space intermediate the 130 tubes or cylinders 3 and 4. The top of the 135 tube or cylinder 4 is flush with the top of the 140 tube or cylinder 3, but the lower end of the 145 tube or cylinder 4 extends through the lamp, 150 as is common in such constructions.

The wick 5 is surrounded by a foraminous 155 section of tubing 6 secured in any suitable 160 manner to the said wick, as by riveting.

The outer cylinder or tube 3 is provided 165 with elongated narrow openings 7 in diag- 170 onally disposed relation with respect to each 175 other, as shown in the drawing, through 180 which extend short pins 8 carried by the 185 opposite sides of a more or less oval shaped bail 190 like member 9 (constituting a double armed 195 lever) provided at a point midway between 200 its opposite ends with a pivot portion 10 sup- 205 ported in a U-shaped bearing member 11 pro- 210 vided at its ends with feet 12 which are se- 215 cured by rivets 13 to the cylinder or tube 3. 220 The portions of the opposite sides of the 225 adjustable member 9 upon opposite sides of the 230 pins 8 are spaced or separated from the cylin- 235 der or tube 3, as indicated in Fig. 2 of the 240 drawing. The member 9 is provided at its 245 opposite ends with outwardly extended par- 250 allel portions 14 spaced a short distance from 255 each other as shown. These portions termi- 260 nate in end projections 15 which extend to- 265 ward each other. In addition to limiting the 270 movement of the parallel portions 14 toward 275 each other these end projections constitute a 280 neat finish. For the purpose of adjusting 285 the opposite sides of the member 9 toward 290 and from each other, I have provided a right 295 and left handed screw threaded rod 16, the 300 opposite end portions of which are in screw 305 threaded engagement with the opposite par- 310 allel projecting end portions 14. The screw 315 threaded rod 16 is provided at its center with 320 a knurled wheel 17 by means of which it may 325 be turned. By turning the screw threaded 330 rod 16 in one direction the opposite sides of 335 the adjusting member 9 may be spread apart 340 so as to withdraw the pins 8 from engage- 345 ment with the wick 5 and the foraminous sec- 350

tion of tubing 6, whereupon the said member 9 may be raised or lowered, and then by turning the threaded rod or screw 16 in the opposite direction the said pins 8 may be caused 5 to reengage the foraminous tube section and wick at different points.

In order that the adjusting member 9 for raising and lowering the wick may be raised or lowered to accomplish the purpose for 10 which it is intended the pivot portion 10 thereof, when the said member is in horizontal position, as indicated in Figs. 1 and 3 of the drawing, should occupy a position a distance from the cylinder or tube 3, so 15 that when the said member is moved up and down about its pivot, the pins 8 traveling at such time in the narrow slots 7, the said pivot portion may slide back and forth in the U-shaped pivot bearing 11. As the ad- 20 justing member 9 is moved either up or down from the horizontal position shown in the drawing, the pivot 10 thereof will slide inwardly toward the cylinder or tube 3.

25 20 designates a flame spreading device of known construction which is supported upon the upper end of the inner wick guiding tube or cylinder 4.

It will be apparent that by my invention 30 I have provided a device which not only is simple and of durable construction, but which may be readily and quickly operated for the purpose of adjusting the wicks of oil lamps, stoves or the like either up or down as may be desired.

35 35 Although I have shown the invention applied to a lamp having a circular wick it will be understood that it is applicable to and may be employed in connection with lamps having flat wicks.

40 40 Although not shown in the drawing, any suitable means may be provided upon the outer side of the upper end portion of the cylinder or tube 3 for supporting a lamp chimney.

45 45 Having thus described my invention, what I claim, and desire to secure by Letters Patent, is:

1. A wick adjusting device, comprising a 50 double armed pivoted lever, the portion connecting the arms constituting the pivot, the said arms encircling the said wick and having inwardly projecting pins to engage the latter, and a stationary bearing in which the said pivot is mounted.

55 55 2. A wick adjusting device, comprising a double armed pivoted lever, the portion connecting the arms constituting the pivot, the said arms encircling the said wick and having means adapted to engage the latter, and 60 an elongated bearing in which the said pivot is mounted, the length of said bearing extending transversely of said wick.

65 65 3. A wick adjusting device, comprising a double armed pivoted lever, the portion connecting the arms constituting the pivot, the

said arms encircling the said wick and having inwardly extending pins in engagement with said wick, which, when the said lever is adjusted to different positions, causes corresponding adjustment of the said wick. 70

4. A wick adjusting device, comprising a double armed pivoted lever, the portion connecting the arms constituting a pivot, the said arms encircling the said wick and having means adapted to engage the latter, a stationary bearing in which the said pivot is mounted, and means for adjusting the said arms toward or from each other. 75

5. A wick adjusting device for adjusting a wick which is supported within a tube, the said tube having longitudinally extending slots situated in opposed relation to each other, the said device comprising a double armed lever, the portion connecting the said arms constituting a pivot, a U-shaped bearing secured to the said tube in which the said pivot is pivotally and slidably mounted, and the said arms being curved around the said tube and having pins secured thereto, which pins extend inwardly through the said slots and engage the said wick, and means for clamping the said arms against the opposite sides of the said tube, substantially as described. 80

6. A wick adjusting device for adjusting a wick which is supported within a tube, which tube is provided with longitudinally extending slots diametrically opposed to each other, the said device comprising a double armed lever, the portion thereof connecting the said arms constituting a pivot, a U-shaped bearing in which the said pivot is pivotally and slidably mounted, and the said arms being curved and extending around opposite sides of the said tube and being provided with inwardly extending pins which project through the said slots to engage the said wick, and adjusting means for adjusting the said arms toward and from each other. 85

7. In a device of the character described, the combination of a tube having elongated slots therein situated in opposed relation with respect to each other, a double armed pivoted lever, the said arms being curved and encircling the said tube, an elongated bearing supported upon the said tube, the said lever being journaled in the said bearing, means upon the said arms for projecting through the said slots to engage the said wick, and means for adjustably connecting the outer swinging ends of the said lever for adjusting the said arms toward and from each other, substantially as described. 90

8. In a device of the character described, the combination of a tube having a couple of oppositely disposed slots therein, which slots extend longitudinally thereof, a wick within said tube, a double-armed pivoted lever extending transversely of said tube and 100

105 110 115 120 125 130

wick, the arms of said lever having inwardly extending pins which project through said slots and engage said wick, and an elongated bearing in which said lever is pivoted, the said bearing extending transversely of said tube and being adapted to permit movement of said lever transversely

of the said tube and wick as it is turned about its pivot.

In testimony that I claim the foregoing 10 as my invention I have hereunto signed my name this 7th day of Feby., A. D. 1921.

JOSEPH C. ROBERT, JR.
